UNITED STATES PATENT OFFICE

2,442,803

WOMAN'S GARMENT

Ruth Usher Garson, Montreal, Quebec, Canada

Application January 24, 1945, Serial No. 574,240
In Canada October 12, 1944

1 Claim. (Cl. 2—73)

1

My invention relates generally to garments. More particularly my invention is directed toward an improved construction for women's garments.

Among the objects of my invention are to devise a garment of the character described that will be attractive in appearance and economical to manufacture; to speed up mass production in the manufacturing of the garments by reducing the quantity of material that would ordinarily be needed and saving considerable amount of time in the cutting and assembly of the same; to construct a garment of the character described that will provide a better fit to the person; and generally to provide a garment of the character described which shall represent a general improvement in the art. Other objects of my invention will become apparent from the description or will hereinafter be pointed out.

In the accompanying drawings:

Fig. 1 is a fragmentary front view of a garment constructed and arranged in accordance with my invention illustrating the same as applied to the person;

Fig. 2 is a fragmentary rear view thereof;

Fig. 3 is an enlarged fragmentary front view of the upper portion of the garment illustrated in Fig. 1; and

Fig. 4 is a rear view thereof.

Referring now in detail to the drawings, the garment illustrated is a woman's undergarment comprising a brassière 11 and made of a suitable material and suitably shaped to conform with the configuration of the body. A belt 12 is secured to the lower edge of the brassière and extends therebeyond on each edge thereof (see Figs. 3 and 4) and the free ends of the said belt 12 are provided with suitable fastening members 13 so that a snug fit around the bust will be provided. Shoulder straps 14 are secured to the upper portion of the brassière and to the belt 12.

A panel 16 is secured to the belt 12 by means of a seam 15 and located below the brassière 11 and in the front portion thereof. This panel 16 is made of suitable material and has outwardly tapering edges which terminate in approximately vertical edges so that the lower portion of the panel is of the same width as a skirt or slip 17 to which it is attached in the following manner: The upper front portion of the slip 17 is sewn at 18 to the lower edge of the panel 16 and the slip 17

2

may be made in the usual manner and is provided with an opening 19 and fastening means 20 which are located at one side of the slip or skirt.

It will therefore be seen from the above description that in accordance with my invention the garment is made with a minimum of parts and instead of having a set of shoulder straps for supporting the slip and another set of shoulder straps for supporting the brassière a single set 10 of shoulder straps is used. Furthermore it is noted that due to the fact that both the slip and brassière are joined at the front by a common member 16 which may be considered the equivalent of a front portion of a waist band a better 15 fit of the garment to the person is obtained and permitting more resiliency in movement to the person wearing such garment.

In the foregoing description the garment is described as used in combination of a slip and 20 a bust support, but it is of course understood that the same features with slight modifications and ramifications may be used for a dress without departing from the essential features as hereinafter described and illustrated.

25 It will thus be seen that there is provided a device in which the several objects of this invention are achieved, and which is well adapted to meet the conditions of practical use.

As various possible embodiments might be made 30 of the above invention, and as various changes might be made in the embodiments above set forth, it is to be understood that all matter herein set forth, or shown in the accompanying drawing is to be interpreted as illustrative and not in a limiting sense.

Having described my invention, what I claim and desire to secure by Letters Patent is:

In a garment, the combination of a brassière 40 comprising breast supporting pockets having a common lower longitudinal edge, a belt permanently secured to the said lower longitudinal edge of said brassière and having portions thereof extending for a distance capable of encircling the body of the wearer and to be fastened together, 45 the free ends of said extending portions having cooperating fastening members to provide a snug fit around the bust, a panel comprising upper, lower and side edges and permanently secured at its upper edge to the said belt and depending therefrom, said panel having outwardly tapering

side edges terminating in approximately vertical edge portions, a slip or similar skirt garment, a front portion of the upper end of the said slip being permanently attached to the lower edge of said panel, the said vertical edges of said panel being spaced apart for a distance substantially equal to the width of the said upper end of said slip, a slitted opening in said slip along one side extending downwardly from the top thereof and releasable fastening means for closing said slitted opening.

RUTH USHER GARSON.
